CLAIM

We claim the ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a second embodiment thereof; and,

FIG. 3 is a third embodiment thereof.

The broken lines in the figures depict portions of the graphical user interface and form no part of the claimed design.

The outer broken lines showing of the display screen or portion thereof form no part of the claimed design.

The shorter tick marks abutting the thicker black portions depict features of the graphical user interface that form no part of the claimed design.
